UNITED STATES PATENT OFFICE.

WILLIAM A. GIBSON AND CHARLES E. NEEDHAM, OF ALLENTEWON, PENNSYLVANIA,
ASSIGNORS TO BRADLEY PULVERIZER COMPANY, OF BOSTON, MASSACHUSETTS,
A CORPORATION OF MAINE.

GRINDING MILL.

Application filed November 16, 1921. Serial No. 515,510.

To all whom it may concern:

Be it known that we, WILLIAM A. GIBSON and CHARLES E. NEEDHAM, both citizens of the United States, and residents of Allentown, county of Lehigh, State of Pennsylvania, have invented an Improvement in Grinding Mills, of which the following description, in connection with the accompanying drawing, is a specification, like characters on the drawing representing like parts.

This invention relates to improvements in grinding mills of the centrifugal type in which a gyratory roll suspended from a driving shaft cooperates with a horizontal grinding ring. The general object of the invention is to provide improved means for driving and lubricating the roll actuating mechanisms.

More specifically, the invention relates to improvements in grinding mills of the type disclosed in the prior Patents No. 1,048,307, Edwin C. Griffin, granted December 12, 1912, No. 1,095,986, Charles E. Needham, granted May 5, 1914, and No. 1,262,379, Charles E. Needham, granted April 9, 1918.

In grinding mills of this type, the gyratory roll which cooperates with the horizontal grinding ring has been suspended upon a universal joint located within the driving element which heretofore has been in the form of a pulley. This pulley has been provided with a downwardly extended hub which formed a part of the universal joint, through which the shaft of the gyratory grinding roll was supported and actuated.

One of the objects of the present invention is to provide a construction in which the universal joint is removed from the driving element, preferably being located at a distance below the driving element, and in such a position as to be readily accessible for repair. This is particularly important since the universal joint is practically the only feature of the mill aside from the grinding roll and die, which needs repair or replacement.

In the grinding mills heretofore constructed, the driving pulley which contained the universal joint, has been located upon a vertical shaft, so that a vertical driving pulley has been always employed. By removing the universal joint from the driving element,

in accordance with the present invention, any type of driving mechanism may be employed, such as a bevelled gear drive from a horizontal shaft, which may be rotated by a horizontal belt or by direct or indirect connection to a motor having a horizontal shaft. The construction is also such that if desired, a motor may be supported directly above the driving shaft, and connected thereto either directly or through suitable well known driving mechanism, such as reducing gears.

Another object of the invention is to provide an improved means for lubricating the universal joint.

Another object of the invention is to provide a novel supporting means for the universal joint, preferably also having means for excluding dust from said universal joint.

A further object of the invention is to provide an improved system for lubricating the bearings of the driving shaft.

These and other objects and features of the invention will more fully appear from the following description and the accompanying drawings, and will be pointed out in the claims. A preferred embodiment of the invention is illustrated in the accompanying drawings, in which—

Fig. 1 is a vertical sectional view of a grinding mill embodying the invention, certain portions being shown in elevation.

Fig. 2 is a front elevation of a grinding mill embodying the invention, showing a modified form of driving mechanism, in which the main driving shaft of the mill is actuated through bevel gearing from a horizontal counter shaft.

Fig. 3 is a partial elevation of a grinding mill embodying the invention, showing the driving shaft of the grinding mill as being actuated from an overhead motor directly connected to it.

A grinding mill comprising a preferred embodiment of the invention as illustrated in Fig. 1, consists of a bed 1, having a pan 2 to receive the material to be ground, and a grinding ring 3 supported in the upper portion of said pan against which the material is ground by a gyratory grinding roll 4, which is secured to the lower end of a shaft 5, which is connected at its upper end through a universal joint to a vertical driving shaft mounted in a super structure sup-

ported from said base. The superstructure which supports the driving shaft and gyroscopic roll shaft preferably is in the form of a U shaped frame 6 extending diametrically across the mill, and rests upon the upper ends of preferably A shaped standards 7, the lower ends of which are seated upon an extension or extensions 8 of the base 1.

The upwardly extending members or arms 10 of the U shaped frame support a saddle 9, which is provided with an upwardly extending central boss 10, which receives and supports the upper bearing for the driving shaft. In the preferred embodiment of the invention disclosed herein, this upper bearing comprises a cylindrical member 11, provided with a central chamber having a preferably spherically concaved lower wall 12 and a downwardly extending, preferably integral, sleeve 13, having a suitable bushing 22 providing a journal for the driving shaft 14. A thrust bearing for supporting the driving shaft is located within the chamber of the upper bearing and comprises an aligning washer 15 having an under, preferably spherically convex, surface complementary to the surface 12 of the bearing, and an upper flat face which supports the lower race 16 of a ball bearing. The upper race 17 of the ball bearing underlies a ring 18 having a downwardly converging central aperture which forms a seat for a conical split nut 19 which is screwed upon the upper end of the driving shaft 14. The bearing member 11 is provided with a suitable cover plate 20 having a central oil inlet which preferably is covered by a suitable hinged cap 21. It will thus be seen that the upper thrust bearing is entirely supported within the chamber 40 by the bearing member 11 which forms an oil receptacle adapted to contain a sufficient amount of lubricant to submerge the thrust bearing.

45 The driving element desirably is connected to the driving shaft a short distance below the upper bearing. Various different types of driving elements may be provided as will hereinafter more fully appear. As illustrated in Fig. 1, the driving element is in the form of a pulley 23, the hub 24 of which is secured to the driving shaft by a suitable key 25. The upper face of the hub of the pulley desirably is provided with a flange 26 to which is secured a cone pulley 27 from which the feed mechanism of the mill is actuated. The cone pulley 27 desirably is hollow, and its base seats tightly upon the upper face of the flange 26 of the hub of the driving element and provides an oil chamber 28 which is adapted to receive any oil which may seep through the upper bearing for the driving shaft.

Desirably the inner wall of the cone pulley converges upwardly so that the centrifugal action of the rotating driving element will

not discharge the oil from the oil chamber thus provided. In the construction herein illustrated the cone pulley surrounds the downwardly extending sleeve 13 of the upper bearing.

The lower bearing of the driving shaft comprises a cylindrical member 30, preferably having a flange 31 which seats upon an annular boss 32 extending upwardly from the transverse web of the U-shaped superstructure 6. An annular channel 33 desirably extends upwardly from the under face of the lower bearing so that a sleeve-like bearing is provided for the driving shaft. The bearing member 30 preferably has an upwardly extending flange 35 which surrounds the lower end of the hub 24 of the driving element and forms a well to which oil may be supplied in any suitable manner. This well also collects any oil which may seep downwardly through the hub of the driving element. A cup 36, to receive the oil which passes through the lower bearing, preferably is secured to the shaft with its wall 37 extending upwardly into the channel 33 in the lower bearing. By reason of this construction any oil which passes through the lower bearing will be collected and retained in said cup so that it cannot drop into the material which is being ground.

One of the principal features of the invention, as above stated, consists in providing a novel universal joint connection between the lower end of the driving shaft and the upper end of the shaft which carries the gyratory roll, said novel connection being substantially the reversal of the construction disclosed in the prior patents aforesaid. 100

In the preferred construction illustrated herein a cross head 38 is secured to the tapered lower end of the driving shaft 14 by a nut 39, or other suitable fastening. This cross head is provided with trunnions 40 which are journalled in segments 41 which slidably engage ways 42 in the complementary member of the universal connection which carries the gyratory roll-carrying shaft, the construction of said segments and ways being similar to those illustrated in the patents aforesaid. 105 110 115 120 125 130 135 140 145 150 155 160 165 170 175 180 185 190 195 The complementary member of the universal coupling desirably is in the form of an oblong chambered coupling member 43 having at its lower end a boss 44 which receives the tapered upper end of the gyratory roll-carrying shaft 5 which is connected thereto by a key 45, or other suitable connection. Diametrically opposite recesses in the inner face of the wall of the coupling member 43 forms seats for the ways 42 which are engaged by the segments 41. The upper end of the chambered coupling member desirably is provided with an outwardly extending flange 46 to which a suitable head 47 is secured by bolts or other fastening. 130

The head 47 is provided with an upwardly extending spherically curved flange 48, the under face of which is engaged by a supporting plate 49 having a recessed under face which receives a wear plate 50 having a spherically curved under face which engages the convex surface of a hardened wear plate 51 which rests upon the cross head 38. By reason of this construction 5 the weight of the roll, its shaft, and the chambered coupling member is carried by the wear plate 50 which is supported by the cross head of the driving shaft. The co-operating curved surfaces of the wear plates 10 50 and 51 enable the roll shaft to have a lateral swinging movement while the roll shaft is rotated upon its axis by the driving shaft through the cross head 38 and the complementary coupling member.

15 It will be observed that the chambered member of the universal coupling is closed at the bottom so that it provides a lubricant receptacle which may be packed with grease or oil, so that the universal coupling members may, if desired, be completely embedded in the grease or oil. The chambered coupling member desirably is provided with a dust cover 52 which has a spherically curved edge fitting in a complementary way 20 formed between the supporting plate 49 and the upwardly curved flange 48 of the head. A helical spring 52^x interposed between the dust cover 52 and the under surface of the cup 37 serves to retain the dust cover firmly 25 in its seat within said way, and to exclude all dust from the universal joint notwithstanding the oscillatory movement of the chambered member of the coupling relative 30 to the driving shaft.

35 By reason of this construction, the universal joint may be located below the superstructure 6, in which the driving elements are journaled, and consequently it may be located within an open portion of the frame, 40 where it is easily accessible for repair or replacement.

The transverse members 53 of the A-shaped standards, which serve to support the usual casing which encloses the grinding 45 chamber and screens, may be so located as to provide a higher and consequently a larger grinding chamber than has heretofore been employed.

In Fig. 1 of the drawing, the driving element for actuating the driving shaft is 50 shown as a pulley.

Another of the principal features of the invention consists in so constructing the grinding mill that it may be driven by various different types of mechanisms, which enables the machine to be readily installed in factories which are provided with different types of power mechanism.

By removing the universal coupling from 55 the driving member, and supporting the

same upon the driving shaft beneath the driving member, means have been provided by the present invention to enable such different driving mechanisms to be employed, certain of which are illustrated in Figs. 2 and 3 of the drawing.

In the construction illustrated in Fig. 2, the driving element comprises a bevelled gear 55, which is keyed to the driving shaft 14 in a manner above described. The bevelled gear 55 is driven through a bevelled pinion 56 upon a counter shaft mounted in bearings 58, formed in one of the vertical webs of the U-shaped superstructure. The counter-shaft may be rotated either by a pulley 59 secured to said shaft, or may be connected to the shaft of a motor 60, or other power transmitting means. Of course, either bevelled, spur or planetary gearing, or other types of power transmitting mechanism may be employed for actuating the driving shaft.

In Fig. 3 a modified form of driving mechanism is illustrated, in which the upper end of the driving shaft 14 is provided with an extension 61, which is connected by a coupling 62 to an overhead motor 63, and may be actuated therefrom either directly or through suitable power transmitting mechanism.

It will be understood that various modifications in form and construction, arrangement and design of parts may be made within the spirit and scope of the following claims.

Having thus described the invention, what we claim as new, and desire to secure by Letters Patent, is:

1. In a grinding mill of the class described comprising an overhead driving shaft, a cross head forming a part of a universal coupling fixedly secured to said driving shaft, a complementary universal coupling member engaging said cross head, and a depending shaft carried by said complementary universal coupling member.

2. In a grinding mill of the class described comprising a vertical driving shaft, a thrust bearing supporting the upper end of said driving shaft, a cross head forming a part of a universal coupling fixedly secured to the lower end of said driving shaft, a chambered complementary coupling member engaging and enclosing said cross head, forming an oil receptacle and a depending shaft carried by said chambered member.

3. In a grinding mill of the class described comprising a vertical driving shaft, a thrust bearing supporting said driving shaft, a cross head fixedly secured to the lower end of said driving shaft, forming a part of a universal coupling, a chambered complementary universal coupling member engaging and enclosing said cross head, a head secured to said chambered coupling mem-

ber, cooperating universal bearing members on said driving shaft and said head acting to support said chambered coupling member, and a depending shaft carried by said chambered coupling member.

4. In a grinding mill of the class described, a vertical driving shaft, a thrust bearing supporting said driving shaft, a cross head fixedly secured to the lower end of said driving shaft, forming a part of a universal coupling, a chambered complementary universal coupling member engaging and enclosing said cross head, a head secured to said chambered coupling member, a bearing member having a convex upper face secured to said driving shaft above said cross head, a complementary concave bearing member engaging the head of said chambered member, and a depending shaft carried by said chambered member.

5. In a grinding mill of the class described comprising a vertical driving shaft, a thrust bearing supporting said driving shaft, a cross head fixedly secured to the lower end of said driving shaft, forming a part of a universal coupling, a chambered complementary universal coupling member engaging and enclosing said cross head, a head secured to said chambered coupling member, a bearing member having a convex upper face carried by said driving shaft above said cross head, a complementary concave bearing member engaging the head of said chambered member, a dust cap fitting said driving shaft, having an edge portion engaging a complementary way on said head, and a gyratory shaft carried by said chambered member.

6. In a grinding mill of the class described comprising a vertical driving shaft, a thrust bearing supporting said driving shaft, a cross head fixedly secured to the lower end of said driving shaft, forming a part of a universal coupling, a chambered complementary universal coupling member engaging and enclosing said cross head, a head secured to said chambered coupling member, a bearing member having a convex upper face carried by said driving shaft above said cross head, a complementary concave bearing member engaging the head of said chambered member, a dust cap fitting said driving shaft, having an edge portion engaging a complementary way on said head, resilient means acting to retain said dust cap tightly seated on said way, and a gyratory shaft carried by said chambered member.

7. In a grinding mill comprising a vertical driving shaft and a shaft connected to the lower end of said driving shaft by a universal joint, a supporting frame having upper and lower transverse members, a bearing for said driving shaft carried by said upper transverse member comprising an oil chamber to receive a thrust bearing, and a

depending sleeve enclosing said shaft, a driving member secured to said driving shaft, having a receptacle to receive the oil which passes through said upper bearing, and a lower bearing for said shaft.

8. In a grinding mill comprising a vertical driving shaft and a shaft connected to the lower end of said driving shaft by a universal joint, a supporting frame having upper and lower transverse members, a bearing for said driving shaft carried by said upper transverse member, comprising an oil chamber to receive a thrust bearing, and a depending sleeve enclosing said shaft, a driving member secured to said shaft, a hollow power transmitting member located above said driving member and actuated thereby, adapted to receive the oil which passes through said upper bearing, and a bearing for said shaft in said lower transverse member.

9. In a grinding mill comprising a vertical driving shaft and a shaft connected to the lower end of said driving shaft by a universal joint, a supporting frame having upper and lower transverse members, a bearing for said driving shaft carried by said upper transverse member, comprising an oil chamber to receive a thrust bearing, and a depending sleeve enclosing said shaft, a driving member secured to said shaft having a receptacle to receive the oil which passes through said upper bearing, a lower bearing for said shaft, mounted in said lower transverse member, having a downwardly extending sleeve embracing said driving shaft, means for supplying oil to said lower bearing and a cup enclosing said sleeve to receive the oil which passes through said lower bearing.

10. In a grinding mill comprising a vertical driving shaft and a gyratory shaft connected to the lower end of said driving shaft by a universal joint, a supporting frame having upper and lower transverse members, a bearing for said driving shaft carried by said upper transverse member, comprising an oil chamber to receive a thrust bearing and a depending sleeve enclosing said shaft, a driving member secured to said shaft having a receptacle to receive the oil which passes through said upper bearing, a lower bearing for said driving shaft mounted in said lower transverse member having an upwardly extending flange surrounding the end of the hub of said driving member and forming an oil receptacle, and provided with a downwardly extending sleeve embracing said driving shaft, and a cup enclosing said sleeve to receive the oil which passes through said lower bearing.

11. In a grinding mill of the class described comprising a vertical driving shaft, and a gyratory roll shaft, a chamber enclosing said gyratory roll shaft, upper and

lower bearings for said driving shaft, a universal coupling connecting said driving shaft and said gyratory roll shaft, located between the lower bearing for said shaft and 5 the top of said chamber, whereby said universal coupling is easily accessible.

12. In a grinding mill of the class described comprising a vertical driving shaft and a gyratory roll shaft connected to the 10 lower end of said driving shaft by a uni-

versal coupling: a frame having transverse members provided respectively with an upper supporting bearing and a lower bearing for said driving shaft, and driving means acting upon said driving shaft intermediate 15 of said upper and lower bearings.

In testimony whereof, we have signed our names to this specification.

WILLIAM A. GIBSON.

CHARLES E. NEEDHAM.
